Claims priority, application Netherlands Jan. 19, 1961
6 Claims. (Cl. 331—78)

This invention relates to a noise generator for microwaves, in which the microwave radiation produced in the positive column of a gas discharge is collected in a cavity resonator.

In a known noise generator for the centimeter wave-range a fluorescent discharge lamp is arranged at right angles to the longitudinal direction of a hollow waveguide, parallel to the largest dimension of the cross section, across the cavity resonator. The discharge is performed substantially completely in mercury vapour, which involves a strong dependence on temperature. With a different structure the gas discharge tube is taken obliquely through the hollow waveguide. In both cases leakage to the outside must be prevented by means of long sleeves at the waveguide openings around the discharge tube.

The plasma of the positive column may be considered in the microwave range as a source of black radiation with a very high equivalent temperature. This radiation is produced during the collision of electrons. The collision frequency should not be excessively low with respect to the frequency at which the noise is measured. If, indeed, the noise associated with the equivalent temperature should be measured, the plasma has to give off its noise energy completely to the waveguide, which requires a complete impedance match between the noise source and the waveguide.

For millimeter waves it is practically impossible to manufacture a gas discharge tube by the existing technological means to serve as a source of noise in the known arrangement. With the restricted choice of discharge conditions (tube diameter and dissipation) it is furthermore difficult to attain a sufficiently high collision frequency of the electrons. A satisfactory matching is therefore not possible.

In a noise generator for microwaves, in which the microwave radiation produced in the positive column of a discharge in a gas is collected in a wave-guide section, the gas discharge tube comprises, in accordance with the invention, an elongated mica window in a rectangular aperture in a metal tube, which window is engaged by a horn antenna having its longitudinal dimension parallel to the tube axis, this antenna going over into the hollow waveguide having a rectangular section for the noise frequency range having wave-lengths below a predetermined wave-length.

With the structure according to the invention an impedance match between the noise source and the waveguide is obtained in a simple manner without the dimensions of the tube preventing the formation of a positive column. The tube may have a fairly large diameter, which involves structural advantages.

With an excessively small depth of the discharge, viewed from the window, the measured noise temperature would remain markedly below the attainable temperature. With a particular embodiment of the invention the arrangement is therefore such that opposite the window a reflector having low losses is arranged. This reflector may be formed by a satisfactorily conductive wall portion or by a separately arranged copper plate. In order to avoid disturbance of the discharge field, the

satisfactorily conductive wall or the separately arranged plate must be enameled.

In certain cases it may be a disadvantage that with the gas discharge extinguished the horn antenna is no longer closed free of reflection. In accordance with the invention this may be solved by arranging a second mica window opposite the first mica window, a horn antenna being also arranged on this second window, which antenna terminates in a reflection-free wedge.

The invention will be described more fully with reference to the accompanying drawing, in which

FIGS. 1 and 2 show a sectional view of a noise generator according to the invention along the axis and at right angles to the axis of the gas discharge tube respectively and

FIG. 3 is a cross sectional view of one embodiment in which impedance matching is satisfactory even in the extinguished state of the gas discharge.

Referring to FIGS. 1 and 2, reference numeral 1 designates a ferrochromium central portion of a gas discharge tube, coated on the inner side with an enamel layer 2. The diameter is about 25 mm. In the glass portions 3 and 4 are arranged the incandescent heating cathode 5 and the flat nickel anode 6 respectively. In a flat side of the portion 1 provision is made of a mica window 7, which is secured in a vacuum-tight manner by means of enamel. The setting of the mica window is engaged by the horn antenna 8, which goes over in the hollow waveguide 9, provided with a connecting flange 10. The ribs of the horn antenna are stiffened as indicated at 11. FIG. 2 furthermore shows the flat, conductive mirror 12 with an enamel layer 13 which, in FIG. 1 is omitted. As shown in FIG. 3 a second window 17 with a horn antenna 18 and a hollow waveguide 19 having a reflection-free wedge 20 of lossy material on the closing plate 21 are arranged opposite the mica window 7.

If the discharge takes place in rare gas, e.g. argon, the equivalent temperature (of a source of black radiation) is 80% of the theoretically attainable value up to a wavelength of about 8 mm. With 4 mm. this value is not more than 60%. A suitable rare gas pressure is about 10 mm. The tube diameter may be chosen considerably smaller.

The tube may, as an alternative, be filled with a non-rare gas, e.g. nitrogen for the examination of the properties thereof, so that universal use is obtained.

What is claimed is:

1. A noise generator for microwaves having wave-lengths below a predetermined wave-length comprising an electric discharge tube including an envelope containing an ionizable gaseous medium at a pressure at which a positive column discharge can be sustained and a pair of electrodes for producing the discharge, said envelope having a longitudinal axis, at least a portion of the envelope constituting a wave-guide section having dimensions substantially greater than said predetermined wave-length, said cavity resonator portion of the envelope having a window therein transparent to microwave energy, a portion of the internal surface of the envelope surrounding the window being covered with a material which avoids disturbance of the discharge field in said wave-guide section, a wave-guide having a rectangular section for the frequency range of said microwaves, and means to couple said wave-guide to said window, said latter means comprising a horn antenna having an outwardly flaring end portion engaging said window and a smaller end connected to said wave-guide, the largest dimension of said outwardly flaring end being parallel to the longitudinal axis of the tube.
2. A noise generator as claimed in claim 1 in which the window is constituted of mica.

3. A noise generator as claimed in claim 2 in which said material surrounding the window is enamel.

4. A noise generator as claimed in claim 3 in which the inner wall of the tube opposite the window is conductive.

5. A noise generator as claimed in claim 4 in which the wall opposite the window is covered with enamel.

6. A noise generator as claimed in claim 1 in which a second window is provided in the wall of the tube opposite the first window, said second window being en-

gaged by a horn antenna which terminates in a reflection-free wedge.
